(57) CLAIM

The ornamental design for a single-sole shoe with orange sole, as shown and described.

DESCRIPTION

The file of this patent contains at least one drawing executed in color. Copies of this patent with color drawing(s) will be provided by the Office upon request and payment of the necessary fee.

FIG. 1 is a perspective view of a single-sole shoe with orange sole shaded to show the color orange, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a back view thereof;

FIG. 8 is a perspective view of another embodiment of our new design of a single-sole shoe with orange sole, where the orange portions are indicated using the USPTO convention of diagonal cross-hatched lines for orange;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a back view thereof.

The broken lines illustrating the half-moon patch, the heel stripe, and the channel on the orange sole in the above described Figures are for illustrative purposes only and form no part of the claimed design.
